UNITED STATES PATENT OFFICE.

HONORAT M. SOULON, OF ODIN, ILLINOIS.

MINER'S EXPANDING DRILL.

SPECIFICATION forming part of Letters Patent No. 593,617, dated November 16, 1897.

Application filed March 13, 1897. Serial No. 627,319. (No model.)

To all whom it may concern:

Be it known that I, HONORAT M. SOULON, a citizen of the United States, residing at Odin, in the county of Marion and State of Illinois, 5 have invented certain new and useful Improvements in Miners' Expanding Drills; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to an expanding drill or reamer for the use of miners; and its object is to provide a tool by means of which the inner end of a drilled hole can be repaired or enlarged, forming a pocket for powder or other 20 explosive material, whereby more efficient results can be obtained than when the blast takes place in a hole of the same diameter throughout.

The invention consists in the novel construction and combination of parts herein-after fully described and claimed.

In the accompanying drawings, Figure 1 is a side elevation view of a tool constructed in accordance with my invention. Fig. 2 is a central longitudinal section of the same. Fig. 3 is a section on line xx , Fig. 2.

In the said drawings the reference-numeral 1 designates a tube or hollow rod provided near its lower end with two diametric slots 2, 35 through which project reamers or cutters 3, the inner ends of which are pivoted to a vertically-movable rod 4. Near its upper end this rod is provided with diametric outwardly-extending pins 5, which project through a slot 6 in the tube 1. Loosely mounted on said tube between the upper and lower pins are washers 7, and between these washers is a lever 8, provided near its center with oppositely-curved arms integral therewith, forming a 40 ring which encircles the said tube and is movable vertically thereon. One end of the le-

ver is pivoted to an arm 9, formed with a half-round bearing 10. A similarly-formed bracket 12 is connected with this arm by bolts 13 for securing the arm to the tube. 50 This bracket and bearing are confined between two collars 14, secured to the tube. A coiled spring 15 is interposed between the pins 5 and the upper end of the tube for depressing the rod 4.

55 The operation is as follows: A hole to receive a blasting charge is drilled in the usual manner. The rod 4 is elevated by the lever 8 drawing the reamers or cutters into the tube, and the latter is then inserted in said 60 hole, and when the tube reaches the bottom the lever 8 will by the spring 15 be depressed, so as to force cutters or reamers 3 outward. By now rotating or oscillating the tube the 65 cutters will ream out and enlarge the inner end of the hole, forming a pocket to receive a blasting charge. By thus enlarging the hole a quantity of powder confined therein will exert considerably more force than a similar charge in a hole of the same diameter 70 throughout.

Having thus fully described my invention, what I claim is—

The combination with the tube having diametric slots at its upper and lower ends, of 75 the vertically-movable rod, the reamers pivoted thereto near the lower end and projecting through the slots in the lower end of the tube, the pins projecting through the slots in the upper end of said tube, the coiled spring, 80 the washers confined between said pins, the lever formed with a central ring encircling said tube between the washers and the arm secured to the tube to which said lever is pivoted, substantially as described. 85

In testimony whereof I affix my signature in presence of two witnesses.

HONORAT M. SOULON.
